UNITED STATES PATENT OFFICE.

EDMUND C. FEY, OF SAN FRANCISCO, CALIFORNIA.

COMPETITIVE COIN-CONTROLLED DISPENSING APPARATUS.

Application filed November 5, 1927. Serial No. 231,180.

This invention relates to a competitive apparatus operated by two or more participants or players who by their skill determine the dispensing of an article, preferably of merchandise, to one or the other, and also the return to the successful contestant or player of the coin or token deposited by him for the purchase of the article, the coin or token of the unsuccessful contestant or player being retained by the apparatus as the purchase price for the article dispensed.

The principal object of the invention is to provide an apparatus the skillful operation of which by two contestants determines the delivery of an article previously purchased by coin or token deposited by both, and wherein the delivery of the article to the successful contestant or player controls also the return of the coin or token therewith. Another object is to enable two contestants to pit their skill of operation of the mechanical means against each other in their endeavor to obtain the delivery to one or the other of the article purchased by both. A further object is to create interest in the dispensing of articles of merchandise from vending machines and to insure the successful contestant obtaining the merchandise contested for and the return of his deposited coin or token.

With the above mentioned and other objects in view, the invention consists in the novel construction and combination of parts hereinafter described, illustrated in the accompanying drawings and pointed out in the claims hereto appended; it being understood that various changes in the form, proportion, size and minor details of construction within the scope of the claims may be resorted to without departing from the spirit or sacrificing any of the advantages of the invention.

Referring to the drawings—

Fig. 1 is a longitudinal sectional view taken vertically through one embodiment of the apparatus.

Fig. 2 is a transverse sectional view taken vertically through the apparatus.

In the drawings, wherein like characters of reference designate corresponding parts 50 —1 indicates a suitable table or support onto which is delivered, in any suitable manner, an article of merchandise 2 dispensed from a suitable vending machine, conventionally illustrated by the numeral 3. The release 55 of the article of merchandise 2 onto the table may be controlled in any suitable manner,

preferably by the deposit of a plurality of coins or tokens, one in each slot 4, and the outward movement of the rod 5, hereinafter more fully described.

The table or support 1 is preferably trough shaped in end elevation and normally assumes a horizontal position, as in Fig. 1, it resting on a supporting rod 6 passing transversely beneath the same, midway between its ends and extending through elongated eyes 7, in depending flanges 8. Coiled springs 9 connecting the lower end of flanges 8 with the bearing rod 10 maintain the table 1 balanced in a horizontal position.

To vibrate the table and tip the same to cause the article of merchandise 2, initially deposited centrally of the table, to travel toward and be discharged from one of its ends into either the chute 11 or 12, each opening at a point exteriorly of the casing 13, suitable mechanism may be provided, the embodiment illustrated being constructed as follows.

Provided with the respective operating 80 cranks 14 located exteriorly of the front wall of the casing 13 are the rotary shafts 17 and 17' journaled in brackets 18, and said shafts connecting respectively through links 19 with the oscillatory frames 20 and 21 85 mounted on the supporting rod 6. The frames 20 and 21 extend in opposite directions from rod 6 and each at its end carries a pivotal pawl 22, their outer ends being free to ride upwardly over an obstruction 90 on the downward movement of its frame and precluded from downward pivoting on their fulcrum by the respective stop pins 23.

Pivottally mounted beyond the free end of each frame 20 and 21 is an arm 24, each 95 normally held in horizontal position by a coiled spring 25, and each carrying at its forward or outer end a pawl 26 mounted similarly to pawls 22. The pawls 26 co-operate respectively with the brackets 27 depending from the other side of the table 1, near its ends.

During the oscillation of frames 20 and 21, their respective pawls 22 on the upward movement of the frames bear against the 105 rear ends of arms 24, forcing the forward ends of the arms downwardly with the pawls 26 lying beneath the brackets 27. As this takes place, the arms 20 and 21 are on their downward movement and their pawls 22 110 have cleared the rear ends of arms 24, enabling the springs 25 to raise the forward

ends of arms 24 and impart a vibratory up and down or tilting movement to the table 1, as the case may be.

The cranks 14 being independently operated, preferably one by each contestant, makes the timing of the pivotal movement of the arms 24 uncertain, and it is the skill in timing the rotation of the crank 14 by one player relative to the operation of the other crank 14 by the contestant that enables the article of merchandise 2 to travel endwise of the table 1 and discharge therefrom into either the chute 11 or 12.

The coin or token deposited in the respective slots 4 passes into an associated slot 28 in a carrier block 29 from which extends the rod 5, and which block reciprocates beneath the discharge end of slots 4.

In its reciprocating movement to the right, 20 in the drawing, the slots 28 in the block 29 pass from beneath the ends of slots 4, and with the deposited coins or tokens arriving on the upper surface of the bearing block 30, register the slots 31 therein. Unless 25 there is a coin or token within each slot 28 at the time the carrier block 29 is attempted to be moved its full distance to the right, the stop surface 32 of one of the stop pawls 33 will contact with the wall 34 and prevent 30 the slots 28 from registering with their respective slots 31.

If a coin or token is in each slot 28, the free end 35 of each pawl rides on its surface and raises the wall 32 above the upper surface 35 of the block 29, enabling the full reciprocating movement of the block to the right.

It is during this transfer movement of the 40 coins or tokens on the outward reciprocation of the transfer block 29 that it is desired to release the article of merchandise 2 from the vending machine 3, and this may be accomplished in many ways, through mechanism connected directly with the block 29 or rod 5, and with the release mechanism of any 45 well known type of vending machine. The coins or tokens when delivered to slots 31, rest therein and are supported by pivoted plates 36, which form directing walls at the upper ends of coin return chutes 37 discharging 50 into chutes 11 and 12.

The angle of disposition of the plates 36 when simultaneously moved from their normal position, Fig. 1, controls the disposal of both of the controlling coins or tokens—one is directed into the casing 13, while the other, that of the successful contestant or player is discharged exteriorly of the casing 13 through its associated chute 37. The plates 36 are connected by a bar 38 and springs 39 normally maintain the plates in their upright position, as illustrated in Fig. 1.

Pivottally connected with each end of the rod 38 is the upper end of a lever plate 40, one projecting into the respective chutes 11 and 12, to be struck by merchandise 2 on

its downward movement through the chute.

Thus it will be observed that the merchandise 2 leaving the end of the table 1 and falling either into chute 11 or 12 travels to a point exteriorly of the casing 13 and encounters in its descent the member 40 in its chute, and in turn so actuates this member that the controlling coin or token deposited by the contestant who has been successful in directing the merchandise through his chute, causes the return of the coin or token to this contestant. The contestant receives the merchandise and the return of his deposited coin or token while the unsuccessful contestant purchases the merchandise, due to the fact that his deposited coin or token is retained within the casing 13.

The rod 5 in the present illustration, Fig. 1, extends exteriorly of the casing 13 from which point it is operated.

Upwardly from the rod within the casing extends an arm 42 carrying a slide plate 43 formed with a single aperture 44. The plate is adapted on the complete outward reciprocation of the rod 5 to receive an article of merchandise 2 from the vending apparatus 3, through the opening 45, the article dropping in the opening 44 in the plate, and such movement deposits the article through the opening 46 in plate 47 onto the center of 95 the table 1.

I claim:—

1. A vending machine comprising a casing provided with a plurality of coin receiving slots and a plurality of coin discharge slots, each communicating both with the interior and exterior of the casing, means whereby the disposal of an article vended is contested for between a plurality of players while the article is within the casing, each player having deposited a coin in one of said coin receiving slots, the winner causing the discharge of the article exteriorly of the machine, and means whereby the article as discharged from the machine releases one of the deposited coins to discharge therewith.

2. A vending machine comprising a casing provided with a plurality of coin receiving slots and a plurality of coin discharge slots, each communicating both with the interior and exterior of the casing, means whereby the disposal of an article vended is contested for between a plurality of players while the article is within the casing, each player having deposited a coin in one of said coin receiving slots, the winner causing the discharge of the article exteriorly of the machine, means whereby the article as discharged from the machine releases one of the deposited coins to discharge therewith and directs the remaining coin interiorly of the casing.

3. A competitive vending apparatus comprising a casing provided with a plurality

- of coin or token receiving slots, a table mounted for vibratory movement and onto which an article to be contested for is deposited, a plurality of slots each adapted 45
 5 for conveying the article of merchandise from the apparatus dependent on where the same discharges from the table, means under the control of a plurality of contestants for imparting vibratory movement to the table
 10 to cause the discharge of the article therefrom through one of said article conveying slots, and means actuated by the delivery of the article for causing the return of one of the coins or tokens with the delivery of
 15 the article.
4. A vending machine comprising a casing provided with a plurality of article discharge stations, means for supporting the articles to be vended, a plurality of operating 50
 20 means each under the control of a different operator for directing the article from the supporting means to one of the discharge stations, dependent on the relative skill of the respective operators, a slot for receiving
 25 a coin, a coin discharge slot communicating with the receiving slot and extending exteriorly of the casing and provided with a branch communicating with the interior of the casing, and means acted on by the article in its passage from its support to one of 55
 30 said discharge stations for directing a coin passing through said discharge slot either into or exteriorly of the casing.
5. A vending machine comprising a casing provided with a plurality of coin receiving slots, adapted each for the reception of a coin or token, and coin discharge means, the latter communicating both with the interior and exterior of the casing, a pair of 60
 35 article discharge chutes leading from the interior of the casing to the exterior, means within the casing for receiving an article and for discharging the same therefrom into one or the other of said chutes, a pair of
 40
- independent operating devices for said means, each of said operating devices actuating said means to discharge the article therefrom into a predetermined chute in accordance with the skill of the operator of the respective operating devices, and means 65
 45 actuated by the article in discharging from the casing for controlling the disposal of both of said coins relatively to the machine.
6. A vending machine comprising a casing provided with a plurality of coin receiving slots and a plurality of coin discharge slots, each communicating both with the interior and exterior of the casing, means whereby the disposal of an article vended is contested for between a plurality of players 70
 50 while the article is within the casing, each player having deposited a coin in one of said coin receiving slots, one contestant causing the discharge of the article exteriorly of the machine, and means whereby as the 65
 55 article is discharged from the machine one of the deposited coins is released to discharge therewith.
7. A competitive vending apparatus comprising a casing provided with a plurality of coin or token receiving slots, a table therein and onto which an article to be contested for is deposited, a plurality of slots each adapted for conveying the article of merchandise from the apparatus dependent on 75
 60 where the same discharges from the table, means under the control of a plurality of contestants for causing movement of the article on the table to cause the discharge of the article therefrom through one of said 80
 65 article conveying slots dependent on the skill of contestants, and means actuated by the discharge of the article for causing the return of one of the coins or tokens with the discharge of the article.

In testimony whereof I have signed my name to this specification.

EDMUND C. FEY.
